Primary Examiner—Prabhakar Deshmukh(74) *Attorney, Agent, or Firm*—Fay, Sharpe, Fagan, Minnich & McKee, LLP(57) **CLAIM**

The ornamental design for a steering wheel lock, as shown and described.

DESCRIPTION

FIG. 1 is a perspective view of a steering wheel lock showing our new design;

FIG. 2 is a top view thereof;

FIG. 3 is a front view thereof;

FIG. 4 is a rear view thereof;

FIG. 5 is a bottom view thereof;

FIG. 6 is a left end view thereof; and,

FIG. 7 is a right end view thereof.

The broken line showings of the steering wheel lock are for illustrative purposes only and form no part of the claimed design.
